(57) **CLAIM**

The ornamental design for a cabinet handle, as shown and described.

DESCRIPTION

FIG. 1 shows a perspective view of a cabinet handle; FIG. 2 shows a right side view of the cabinet handle; FIG. 3 shows a left side view of the cabinet handle; FIG. 4 shows a top plan view of the cabinet handle; and FIG. 5 shows a bottom plan view of the cabinet handle. FIG. 6 shows a rear view of the cabinet handle; and, FIG. 7 shows a front of the cabinet handle.

The broken lines in the drawings illustrate environmental subject matter that forms no part of the claimed design. The cabinet handle is shown with a symbolic break in its length. The appearance of any portion of the article between the break lines forms no part of the claimed design.
